UNITED STATES PATENT OFFICE.

DE WITT C. SCUGAL, OF SEATTLE, WASHINGTON.

AUXILIARY VISE AUTOMATIC.

Application filed April 7, 1927. Serial No. 181,694.

The invention is an attachment for linotype, intertype or line casting machines which works in conjunction with the normal operation of the machine and automatically operates to stop the machine when using the high mold when the operator neglects to utilize the first elevator slide filling piece.

The object of the invention is to provide an automatic safety stop which will not interfere with the normal operation of the machine and which will automatically stop the machine when the first elevator travels beyond the correct position.

Another object of the invention is to provide means for constructing the vise automatic stop mold disc dog which will permit the lower half of the dog to slide to automatically operate the safety device when the machine is operating normally while the upper half remains stationary.

A further object of the invention is to provide a slidable attachment on the vise automatic stop rod which will engage the upper portion of the dog.

A still further object of the invention is to provide a slidable attachment on the vise automatic stop rod which will not interfere with the normal operation of the machine.

And a still further object of the invention is to provide an attachment for automatically stopping the machine when the first elevator slide fails to stop at the correct position, which is of a simple and economical construction.

With these ends in view the invention embodies a split dog which will replace the vise automatic stop mold disc dog, a bar slidably held on the vise automatic stop rod, a pin extending upward from the said bar and adaptable to engage the under side of the head of the elevator slide, a spring for resiliently holding the bar upward, and a clip that may be attached to the mold disc adjacent the mold opening.

Other features and advantages of the invention will appear from the following description taken in connection with the drawings herein:

Figure 1 is a sectional view through the first elevator and mold of a linotype machine with parts omitted showing the device ready to use the high mold with the first elevator slide in the upper position.

Figure 2 is a similar view showing the slide in the lower position before the disc

has moved toward the elevator and when the operator has failed to use the first elevator slide filling piece.

Figure 3 is a similar view showing the device in the normal operating position when using the lower mold.

Figure 4 is a detail showing a longitudinal section through the vise automatic stop mold disc dog.

Figure 5 is a similar view showing the lower half of the stop mold disc dog as it is normally moved by the mold on the disc.

Figure 6 is a side view of the first elevator with parts omitted which shows the position of the first elevator slide filling piece.

In the drawings the device is shown as it would be made wherein numeral 1 indicates the vise automatic stop mold disc dog, numeral 2 the bar which is slidably held on the vise automatic stop rod, and numeral 3 a removable clip that is only used when the upper mold is being used. The disc dog 1 is made as shown in Figure 4 with an upper section 4 and a lower section 5 and a spring 6 in a circular opening 7 between the two sections. It will be noted that the upper section is provided with a projection 8 at one end that extends downward into the circular opening 7 and the lower section 5 is provided with a projection 9 that extends upward into the circular opening 7 so that one end of the spring will engage the projection 8 and the other the projection 9 which will cause the two members to be resiliently held in the position shown and it will be observed that the lower section may move to the position shown in dotted lines in Figure 4 while the upper section 95 remains stationary. This dog is slidably mounted in the circular opening provided in the frame for the vise automatic stop mold disc dog.

The bar 2 is vertical and slidably held by a U-shaped band 10 which is placed around the vise automatic stop rod which is indicated by the numeral 11 and at the upper end of the bar 2 is a lever 12 which is pivotally attached to it by a pin 13 and which extends upward through the elevator frame which is indicated by the numeral 14 to a point 15 so that it will engage the under side of the first elevator slide head as it moves downward. The lever 12 is provided with a spring 16 which is attached to an eye 17 on the under side of the frame 14 to

resiliently hold the lever and bar 2 in the upper position shown in Figure 1. It will be understood that any other suitable means may be used for slidably mounting the bar 2, for moving it downward when the elevator slide moves beyond the correct position, and for resiliently holding it upward.

The clip 3 may be readily attached to the disc adjacent the mold when using the upper mold and it will be observed that it will engage the upper portion of the dog 1 and thereby force the dog against the lower end of the bar 2 when the operator has neglected to throw the filling piece into place as indicated by the numeral 18, and the head of the elevator slide has moved downward beyond the correct position. It will be noted in Figure 5 that the filling piece 18 is pivotally mounted on the first elevator frame at the point 19 and when the upper mold is being used it is thrown over from the position shown in full lines to the position shown in dotted lines so that it will engage the under side of the upper end of the first elevator slide.

It will be noted that in the normal operation of the machine a screw as indicated by the numeral 20 and located in the upper end of the elevator slide engages a pin 21 at the upper end of the vise automatic stop rod 11 and forces this rod downward so that a projection 22 will pass below the under side of the dog 1 and permit the dog to move outward to the position shown in Figure 3; however when the first elevator slide fails to move downward to the proper position the pin 21 is not moved downward so that the dog 1 will engage the projection 22 and prevent the mold disc moving over so that the machine will stop. This new device operates to stop the machine when the elevator slide moves downward too far when the upper mold is being used as when the slide moves downward to such a position it moves the bar 2 downward with the clip 3 in place the clip 3 will force the dog 1 against the bar 2 and stop the machine.

It will be understood that changes may be made in the construction without departing from the spirit of the invention, one of which changes may be in the design or arrangement of the dog 1, another may be in the use of other means for supporting the bar 2 or in the use of a bar of another design, and still another may be in the use of other means to engage the upper half of the dog 1 instead of the clip 3.

The construction will be readily under-

stood from the foregoing description. To use the device the dog 1 and the bar 2 may be readily attached to or built into the machine and may remain in place while the machine is being used to operate with either the upper or lower mold. When using the upper mold the clip 3 may be attached to the disc and it will be observed that it will function to stop the machine when the first elevator slide moves beyond the correct position.

Having thus fully described the invention what I claim as new and desire to secure by Letters Patent, is:

1. In a device of the class described, a split dog with both members resiliently held endwise, said dog being adaptable to replace the vise automatic stop mold disc dog of a casting machine, a clamp adaptable to be attached to the mold disc to engage the upper portion of the said dog, a bar slidably on the vise automatic stop rod, means for moving the said bar downward to engage the upper portion of the said dog when the first elevator slide fails to stop at the correct position and means for resiliently holding the said bar upward.

2. In a device of the class described, a split dog, means for resiliently holding the sections, one of the said sections being adaptable to be engaged by the mold on the mold disc, removable means for engaging the other of the said sections, a bar slidably mounted on the stop rod and adaptable to be engaged by one of the sections of the said dog, and suitable means for operating the said bar as desired.

3. In a device of the class described, a split pin adaptable to replace the vise automatic stop mold disc dog of a casting machine, one section of the said pin being adaptable to be engaged by the mold on the said mold disc, a clip on the said mold disc for engaging the other of the said sections and means for engaging the opposite end of the said pin to stop the operation of the machine as desired.

4. In a device of the class described, a resiliently held split pin adaptable to replace the stop dog of a line casting machine, said pin adaptable to permit the machine to operate normally, and means adaptable to engage the said pin to stop the operation of the said machine when the elevator slide fails to stop at a correct position.

In testimony whereof I affix my signature.

DE WITT C. SCUGAL.
